COIN TESTER FOR VENDING MACHINES

Arthur H. Kramer, Uniontown, Pa.

Application September 7, 1935, Serial No. 39,617

2 Claims. (Cl. 194—103)

This invention relates to dispensing machines and more particularly to a coin testing or selecting means for a coin operated dispensing machine.

5 An object of this invention is to provide a coin testing or selecting means whereby articles in the form of checks or slugs having a weight either lighter or heavier than a predetermined coin will be rejected and prevented from passing 10 to the operating means actuated by the predetermined coin in the dispensing machine.

Another object of this invention is to provide a testing or selecting means whereby the operation of the selecting means is determined by a 15 coin of a predetermined value so that the selecting or rejecting means can be used for coins of different values.

The above and various other objects and advantages of this invention will in part be described in, and in part be understood from the 20 following detail description of the present preferred embodiment, the same being illustrated in the accompanying drawing, wherein:—

Figure 1 is a top plan view of a coin testing or rejecting means constructed according to an 25 embodiment of this invention.

Figure 2 is a sectional view taken on the line 2—2 of Figure 1.

Figure 3 is a sectional view partly in front elevation taken on the line 3—3 of Figure 1.

30 Referring to the drawing wherein like numerals of reference designate corresponding parts throughout the several views, the numeral 10 designates generally a channel or coin guiding means which is preferably inclined to the horizontal so that a coin will freely roll from one end to the other. This channel 10 is adapted to be mounted in a dispensing machine and is adapted to be associated with the coin operated means 35 carried by the dispensing machine.

The channel or guide member 10 is provided with a pair of coin outlets 13 at spaced points therealong and each outlet 13 is of a size substantially smaller than a coin or check 11, as shown 40 in Figure 3.

45 In order to provide a means whereby slugs or checks or more or less weight than the normal weight of the coin 11 may be prevented from passing to the coin operated means for the dispensing means associated with this device, I have provided an initial coin rejecting member, generally designated as 12, which is disposed between a pair of brackets 14 which are secured to one side of the channel 10. These brackets have 50 threaded pivotal members 15 threaded there-

through which engage at opposite sides of the coin rejecting member 12, so as to rockably mount this member 12 between the brackets 14.

The trunnions 15 are locked, as by lock nuts 16. The coin rejecting member 12 comprises a plate 5 17 having upturned or downturned flanges or side portions 18 which are engaged by the trunnions 15. The rejecting member 12 has a hopper 19 which is disposed at an angle to the plate 17, as shown in Figure 2, and this hopper or guide member 19 discharges into a receiving member 20, which may be connected to a channeled means for returning the rejected coin or slug to a predetermined point on the dispensing machine. The hopper or nozzle 19 is disposed on the same 15 side of the channel member 10 as the opening 13 so that the rejected slug or coin 11 will drop on to this guide member 19 and effect a tilting of the member 12, as shown in dotted lines in Figure 2, so that the rejected slug or coin will readily 20 slide downwardly on to the receiving member 20.

The rejecting member 12 is provided at its rear end with a coin or check receiving slot 21 and preferably the plate 12 is bent upwardly, as at 22, on opposite sides of the slot 21 to provide a clamping means to clamp the coin 11a on to the inner end of the plate 17. The plate 17 is also provided with a substantially U-shaped clip 23, which is secured as by a bar or securing member 24 to the underside of the plate 17 and this 25 clip coats with the upturned portions 22 in firmly holding the coin 11a in the slot 21.

The plate 17 is provided with an elongated opening 25 and an adjustable balancing member 26 is disposed within this opening 25 and 30 is mounted on a threaded bar 27 secured substantially centrally of this opening 25. The threaded adjusted member 26 may be moved along the length of the opening 25 to the desired point so that when the slug or check having a 35 weight greater than the weight of the coin 11 arrives at the opening 13, this overweighted slug or check will rock the member 12 downwardly and thus release the slug or check from the channel member 10 so that this rejected article will 40 slide downwardly into the receiving member 20.

A second rockable member 12a is mounted between a second pair of brackets 14a disposed in spaced relation to each other and secured to the channel member 10 on the same side as the 50 brackets 14. This member 12a is rockably mounted between a pair of trunnions 15a threaded through the bracket members 14a, which are locked by lock nuts 16a. The rockable member 12a comprises a plate 17a having side flanges 18a 55

and the forward end of the rockable member 12a is provided with a chute or guide member 19a which discharges into a coin receiving member 20a. The plate 17a is provided with an opening 25a and an adjustable balancing member 26a is threaded on to a bar 27a secured to one side of the plate 17 and in substantially the transverse center of the opening 25a. The rear portion of the plate 17a has a coin receiving opening 21a and the plate 17a is provided with upturned guide or clamping members 22a similar to the plate 17.

As shown in Figure 1, the balancing member 26a is adjusted to a different position from the 15 balancing member 26 so that when a coin having a weight similar to the weight of the coin 11a arrives at the opening 13a, having successfully passed the rejecting member 12, the rockable member 12a will rock downwardly at its forward end so that this correctly weighted coin 11 will slide down the guide member 19a and into the receiving member 21a. The coin entering the receiving member 21a will then pass to the vending machine.

25 The guide member or chute 19 has a guard 28 one side thereof, as shown in Figure 1, so as to prevent coins from initially rolling off of the chute 19 and a guard member 29 is also provided on the forward side of the channeled member 10 adjacent the guard 28 so that when the rockable member 12 rocks downwardly under the weight of a rejected check or slug the tilting over of this slug or check will not cause the rejected article to roll off of the chute or guide member 19.

30 The second rockable member 12a is also provided with a guard 28a and the channel member 10 has a guard 29a to prevent the tilting coins from rolling off of the channel or chute 19a when this chute 19a rocks downwardly under the weight of a coin having a weight similar to the coin disposed in the slot 21a.

40 In the use of this coin testing or rejecting means, the channel 10 is disposed within the conventional dispensing machine with the receiving member 20 connected to a suitable coin or check returning means and the receiving member 20a connected to the usual coin operated mechanism. The channel member 10 is disposed on a sufficient angle to the horizontal so that coins or checks will freely roll therealong. The receiving end of the channel 10 may be at either end or, in other words, the channel member 10 may be positioned with one or the other 45 end uppermost.

45 In the present instance, the channel member 10 has the end to the left of Figure 1 uppermost and this end constitutes the receiving end in which the coins are deposited. A coin similar to that which is used to operate the dispensing means is inserted in the slot 21 and the adjusting or balancing member 26 is then moved along the threaded bar 27 so that when coins of the same weight roll along the channel member 10, these normal coins will not rock the member 12 downwardly and will, therefore, not be deposited in the rejecting channel 20. The rockable member 12a is balanced in a similar manner to the member 12, that is, by inserting a coin 50 in the slot 21a of the same character as the coin which is adapted to operate the vending machine. The balancing member 26a is then adjusted along the length of the bar 27a so that any coin or slug of the same weight as the coin

disposed in the slot 21a will rock the member 12a downwardly at its forward end so that the acceptable coin or check will slide down the chute or guide member 19a and into the receiving channel 20a. In the event a lighter coin of the 5 same or less value as the coin in the slot 21a passes the rejecting member 12, this light coin or check will not have a sufficient weight to rock the member 12a downwardly and will, therefore, pass along the channel 10 past the rockable member 12a and may be returned to the depositor or guided to some remote point in the vending machine.

10 It will, therefore, be apparent that the two rockable members 12 and 12a are initially balanced by a coin of the same character as the coin which is used to operate the vending machine so that it is possible to very finely adjust these two members 12 and 12a in order to reject overweight checks or slugs and also to reject 15 lightweight coins or checks. It will be apparent from the foregoing that the rejecting of the slugs or coins is effected without the use of magnetic means so that irrespective of the quality 20 of the check or coin, if the article does not have exactly the same weight as the weight of the coin in the slot 21a, the coin or check will be rejected, thus preventing operation of the vending machine by counterfeit coins, slugs or similar articles.

25 30 I claim:—

1. In a testing device, a coin chute provided with elongated spaced apart discharge openings in the bottom, a pair of plate members disposed transversely of said chute and positioned with the inner end of each plate across an opening of the chute, upstanding sides carried by each plate, a pair of outstanding arms for each plate carried by the chute, pivot means carried by said arms and engaging the sides of a plate to pivotally secure a plate to the chute, each plate having an elongated opening in substantially the center thereof, a threaded bar carried by the plate extending longitudinally of the opening, a threaded balancing member on said bar and movable longitudinally of a plate, each plate having a coin receiving slot adjacent the outer end thereof, and a U-shaped clip carried by each plate beneath said coin slot for removably holding a coin in said slot.

40 45 50 55 60 65 70 75 80 85 90 95 2. In a testing device, a coin chute provided with elongated spaced apart discharge openings in the bottom and in a side thereof, a pair of plate members disposed transversely of said chute and positioned with the inner end of each plate across a bottom opening of the chute, upstanding sides carried by each plate, a pair of L-shaped arms for each plate having one leg thereof secured to a side of the chute opposite from the side opening thereof, pivot means carried by said arms and engaging the sides of a plate to pivotally secure a plate to the chute, each plate having an elongated opening in substantially the center thereof, a threaded bar carried by the plate extending longitudinally of the opening, a threaded balancing member on said bar and movable longitudinally of a plate, each plate having a coin receiving slot adjacent the outer end thereof, a U-shaped clip carried by each plate beneath said coin slot for removably holding a coin in said slot and a guard member secured to the chute at an end of each side opening.
